S. G. THOMASSON

SCRAPER FOR CARBIDE LAMPS

Filed June 12, 1923

Inventor:
S. G. Thomasson

By *Placencia O'Brien*
Attorney.

UNITED STATES PATENT OFFICE.

SAMUEL G. THOMASSON, OF JASONVILLE, INDIANA.

SCRAPER FOR CARBIDE LAMPS.

Application filed June 12, 1923. Serial No. 644,844.

To all whom it may concern:

Be it known that I, SAMUEL G. THOMASSON, a citizen of the United States, residing at Jasonville, in the county of Greene and 5 State of Indiana, have invented certain new and useful Improvements in Scrapers for Carbide Lamps, of which the following is a specification.

In carrying out the present invention, it is 10 my purpose to provide a scraper within the usual carbide receptacle of miners' lamps, whereby during the attachment or detachment of the receptacles to the water containers of the lamps, the carbide will be effectively scraped from the walls thereof.

The primary object of this invention is 15 the provision of such a scraper that is embodied directly within the said carbide receptacle, and is of an extremely simple construction, and one that may be incorporated with carbide lamps at a minimum expenditure.

The nature and advantages of the invention will be better understood when the following detailed description is read in connection with the accompanying drawings, 20 the invention residing in the construction, combination, and arrangement of parts as claimed.

30 In the drawings forming part of this application, like numerals of reference indicate similar parts in the several views, and wherein:

Figure 1 is a side elevation, partly in cross 35 section of a conventional type carbide lamp, the carbide container thereof being equipped with my improved scraping means.

Figure 2 is a detail transverse cross section upon the line 2—2 of Figure 1, looking 40 downwardly in the direction of the arrows.

Figure 3 is a vertical cross section upon the line 3—3 of the same figure, and

Figure 4 is a transverse cross section upon the line 4—4 of the same figure and looking 45 upwardly in the direction of the arrows.

Referring to the drawings in detail, there is shown a carbide lamp of conventional form embodying a water receptacle 5, and carbide container 6. The said water receptacle 5 is formed with the usual pendent 50 outwardly flaring skirt portion 7, that is screw threaded at 8 for engaging the screw threads 9 of the usual neck 10 that is formed upon the upper end of the inwardly converging portion 11 of said carbide container 6.

My improvement embodies the provision of a pair of plate elements 12 that have close contact with the interior of said carbide container and converge inwardly at 60 their upper ends at 13 for close contact with the inwardly converging portion 11 of said container. The ends of said inwardly converging portions 13 of the plates are integrally joined together by a ring 14, that is 65 formed at diametrically opposite points with inwardly extending ears 15, each of which is formed with an opening and adapted for the reception of pendent pins 16, that are formed upon the bottom wall of the 70 water receptacle 5 and engage through openings in a leather washer 17. This washer being present for obvious purposes.

The lower ends of the plates 12 are integrally joined together, by a cross plate 18, 75 this cross plate being centrally, loosely secured to the bottom wall of the carbide container 6 by a pivot element 19.

The plates 12 as well as their inwardly converging portions 13 are formed with 80 teeth 20 upon opposite vertical edges thereof, it being noted from a consideration of Figure 2, that these plates are slightly arcuate shaped for conforming to the curvature of the container 6. The connecting 85 plate 18 between the lower ends of said plates 12 is also formed with teeth 21, the teeth in this instance being formed upon opposite edges of the cross plate that are at opposite sides of said pivot element 19. 90

In view of the above description, it will at once be apparent that as the container 6 is being engaged with the water receptacle 5, the pins 16 of the water receptacle will engage within the openings of said ears 15 of the ring 14, whereby through a continued rotary movement of the container 6 with respect to the water receptacle 5, the plates 12 and connecting plate 18 will be rotated and effectively scrape the carbide from the walls 95 of the container. It is of course to be understood that the edges of the plates 12 and cross plate 18 that carry said teeth are cutting edges as more clearly shown in Figure 2. 100

Between the upper ends of the plates 12, there may be, and preferably is provided a reinforcing ring 20 that is riveted or otherwise secured to these plates, this ring effectively preventing displacement of the 110 plates with respect to the interior surface of the carbide container 6. 105

Numerous advantages of a scraper for carbide lamps of the present character will be at once apparent to those skilled in the art, and even though I have herein set forth 5 the most practical embodiment of the invention with which I am familiar, it is nevertheless to be understood that minor changes may be made therein, without departing from the spirit and scope of the invention as 10 claimed.

Having thus described my invention, what I claim as new, and desire to secure by Letters Patent, is:

A carbide lamp comprising a water container, and a generating chamber having 15

screw threaded engagement with said water container, pins carried by the bottom of said container and adapted to project into the generator chamber, when engaged with said container, a frame turnably mounted in said chamber and having a scraper blade adapted to move along the inner surface of the wall of said chamber, said frame being formed with openings adapted to receive said pins whereby the removal and attachment of the generating chamber to said water chamber effects a rotation of the scraper in the chamber. 20 25

In testimony whereof I affix my signature.
SAMUEL G. THOMASSON.
